UNITED STATES PATENT OFFICE.

RUFUS DUTTON, OF YONKERS, NEW YORK.

IMPROVEMENT IN HARVESTER-CUTTERS.

Specification forming part of Letters Patent No. 157,592, dated December 8, 1874; application filed February 3, 1874.

To all whom it may concern:

Be it known that I, RUFUS DUTTON, of the city of Yonkers, in the county of Westchester and State of New York, have invented a new and useful Improvement in Fastening Fingers to the Finger-Bars of Harvesting-Machines; and I do hereby declare that the following is a full, clear, and exact description thereof, and of the mode or manner of operation, reference being had to the accompanying drawings and to the letters of reference marked thereon, and making a part of this specification.

My invention relates to an improved method for keeping the front ends of fingers in place, both laterally and vertically, when attached to the bar.

Figure 1 represents the top view of a section of a finger-bar with the finger attached. Fig. 2 is a side view of the same. Fig. 3 is a sectional view of the same, showing the method of fastening the finger to the bar.

A represents a section of a finger-bar rolled

or turned up at its front edge *d*. B shows the finger. The under surface of the slot of the finger comes in contact and in line with the upper edge of the finger-bar at *b*. *a* is a bolt, which fastens the finger to the bar. *c* is what is termed a steady or dowel pin, driven firmly in the finger. There is a corresponding hole drilled in the bar, for the reception of the other end of the pin. When the finger is attached to the bar, and bolted firmly with the bolt *a*, the pin *c* keeps the end of the finger from being displaced when in use.

What I claim as my invention, and desire to secure by Letters Patent, is—

The combination of the finger-bar, the finger, the bolt, and the steady or dowel pin, substantially as and for the purpose set forth.

RUFUS DUTTON.
